KILN.

No. 841,847.

Specification of Letters Patent.

Patented Jan. 22, 1907.

Application filed August 23, 1906. Serial No. 331,761.

To all whom it may concern:

Be it known that I, PAUL CHMELEWSKI, a subject of the Czar of Russia, residing at Helsingfors, in the county of Nyland, Finland, Russia, have invented certain new and useful Improvements in Kilns; and I do declare the following to be a full, clear, and exact description of the invention, such as will enable others skilled in the art to which it appertains to make and use the same.

This invention relates to improvements in brick and pottery kilns of the continuous type; and it consists in the construction, combination, and arrangement of devices, hereinafter described and claimed.

The object of the invention is to provide a kiln of this character which will be of simple, durable, wider, and comparatively inexpensive construction and in which a greater number of bricks or the like may be more perfectly burned than in the kilns now in general use.

The above and other objects, which will appear as the nature of the invention is better understood, are accomplished by the construction illustrated in the accompanying drawings in which—

Figure 1 is a top plan view, with parts in section, of my improved continuous drying and burning kiln. Fig. 2 is a side or front elevation of a portion of the same. Fig. 3 is a vertical transverse sectional view taken on the plane indicated by the line 3-3 in Fig. 1. Figs. 4 and 5 are vertical longitudinal sectional views taken, respectively, on the planes indicated by the lines 4-4 and 5-5 in Fig. 1. Fig. 6 is an enlarged vertical transverse sectional view taken on the plane of the line 6-6 in Fig. 1, and Fig. 7 is a diagrammatic view illustrating the continuous operation of the same.

My improved kiln comprises an inner or center wall 21, an outer surrounding side wall 22, which forms between its inner face and the center wall a continuous chamber 23, adapted to be temporarily divided into separate compartments during the operation of the kiln, these compartments in the drawings being numbered consecutively from 1 to 20, as shown in Figs. 1 and 7. The surrounding wall 22 preferably consists of two straight sides united at their ends by either rounded or square end walls, which are spaced from the ends of the center or inner

wall 21, the latter being of less length than the sides of the outer wall. These walls may be of any form and construction and are built upon a suitable foundation, which is preferably housed in or covered, as shown in the drawings. The bricks or other articles to be burned are introduced into the compartments of the continuous or endless chamber 23, through door-openings 24, formed in the outer wall 22 at suitable points adjacent to its bottom, and in the bottom of said wall at points between the filling openings 24 are formed smaller openings 25, through which fuel may be introduced into the sections or compartments of the chamber 23, as herein-after described.

After one of the sections or compartments of the chamber 23 has been filled with green bricks or the like its filling-opening 24 is closed by brickwork or masonry, and a fire-opening similar to one of the openings 25 is formed in such brickwork. The openings 25 are provided for introducing fuel into the kiln for the purpose of drying the green bricks—that is, removing the moisture from them and bringing them to a temperature of about 100° centigrade, at which temperature they will not be injured by the gases from the bricks being subjected to a much greater heat in another part of the kiln, as will be presently explained. After the brick mass in one of the compartments has been sufficiently dried or has been brought to the required temperature the fire-openings 25, also the openings in the doors 24 and the holes 31 in the top covering of the brick mass, are bricked up or closed by masonry.

The kiln has no permanent top or arch; but each of its sections or compartments is covered with a temporary top 27, which is supported upon the brick mass 28 after the latter has been placed in position. This brick mass 28 is so made up that spaces or channels are formed between the bricks or other articles of which it is composed in order to permit the heat and products of combustion from the fire to circulate between them, and the top or covering 27 is preferably composed of two layers 29, 29 of old bricks and a top coating or layer 30 of earth or the like. In these temporary top or cover sections of the compartments of the chamber 23 are formed outlet-openings 31, through which escape the smoke and products of

combustion from the fuel introduced through the openings 25 and through the openings in the doors 24 and the steam and gases from the green brick mass 28. A row of these openings 31 is preferably provided in each of the top sections adjacent to the center or inner wall 21, so that the heat and products of combustion will be caused to travel diagonally across the compartment, as will be seen upon reference to Fig. 6 of the drawings. The openings 31 are adapted to be bricked up or closed when the fire-openings 25 are closed, as hereinafter described. In each of the top sections 27 are also formed a plurality of fire-openings 32, through which fuel is introduced into the kiln for the purpose of producing a very high temperature in the same and thoroughly burning the brick mass. These openings are in vertical alignment with suitable openings or spaces between the bricks or articles in the brick mass 28. These openings are provided with removable covers or closures made of metal, in order that fuel may be introduced through them to produce a very high temperature and finish the burning of the bricks in that part of the kiln.

The heat and products of combustion from the fuel introduced through the openings 32 and the gases given off by the brick mass from the effects of the same upon it are discharged from the burning-chamber 23 through outlet-passages 36, formed in the center or inner wall 21, adjacent to its bottom, and adapted to communicate with a longitudinally-extending smoke-flue 37, also provided in the upper portion of said wall. This smoke-flue may be located also under the center or inner wall 21, also in the surrounding side wall 22 or under the furnace foundation.

Suitably cone-shaped valves 38, operated by rods 39, are arranged in the smoke-flues 37 and coat with valve-seats 40, provided at the upper ends of the passages 36, so that the latter may be readily opened and closed. The outlet in the longitudinally-extending smoke-flue 37 may be located at the center of the kiln or otherwise, as above stated, and extends downwardly and under the furnace foundation, as shown at 41 in dotted lines in Fig. 3, and then to a suitable smoke-stack 42. In the center wall 21 are also provided manholes 43 to permit of the cleaning out of the flue 37, and in said wall are also provided chambers or spaces which are filled with sand or the like 44, vertical passages 45 being provided in the wall 21 to permit of the introduction of the sand and to permit of the escape of gases from said chambers or spaces. Upon the top of the center wall 21 is preferably provided a track 46, upon which cars may be run for the purpose of carrying fuel to the fuel-openings 32, suitable shelves 47, being arranged in the housing 48 of the kiln

for the purpose of supporting such fuel above and to one side of the body of the kiln, so that it will not be subject to the heat upon the top of the same. Suitable bridges or inclined trestles 49 are provided at each of the ends of the kiln to permit the fuel-carrying cars to be run upon and off of the top of the same.

In order to divide the continuous or endless chamber 23 into sections or compartments in which the bricks may be dried and heated before they are burned, I provide temporary removable partitions 50, formed of one or more vertically-removable plates or sections of metal or other material which will not be affected by the heat in the kiln. As shown, each of these partitions 50 consists of three separate metal plates, and five of such partitions are employed in the kiln shown. These partition-plates slide vertically and are raised and lowered by means of cables, chains, or other flexible connections 51, passed over pulleys or blocks 52 in the frame 48 and each having one of its ends attached to the top of one of the partition-sections and its other end hanging within convenient reach of an operator or attached to a suitable hoisting mechanism. During the operation of the kiln these partitions are changed, so that they separate different compartments of the chamber 23, as presently explained.

The operation of the kiln will be readily understood upon reference to Fig. 7 of the drawings, in which the twenty compartments or sections of the continuous chamber 23 are diagrammatically represented by the numbered blocks or spaces. In Fig. 7, 1 denotes the compartment which is being filled with green bricks. 2 denotes the compartment that has just been emptied. 3 denotes the compartment from which the finished bricks are being removed. 4, 5, 6, 7, and 8 denote the compartments having different temperatures and in which the burned bricks are gradually cooling and through which air is supplied to the two compartments 9, 10, in which latter fuel is introduced through the top through the openings 31 and 32 to raise the temperature therein to a very high degree. 11, 12, 13, 14, 15, and 16 denote the compartments which have gradually-decreasing temperatures and through which the heat, gases, and products of combustion pass from the fire in the compartments 9, 10, as indicated by the arrows, to the discharge or outlet in the compartment 16, which discharge-outlet leads to the smoke-stack 42. 17, 18, 19, and 20 denote compartments separated by the temporary removable partitions and in which green bricks are being dried by the burning of fuel introduced through the fire-openings 25 in the side wall of the kiln and the opening in the door, the fire in section 20 having just been started and

the fires in the sections 19 18 17 being each about a day older than the next adjacent, so that the temperatures in said compartments 17 18 19 20 vary, as indicated. In using the 5 kiln the green bricks or pottery of any description are introduced into one of the compartments through the door 24, and after such compartment is filled the temporary top 27 is formed upon the top of the brick 10 mass, and the door 24 is closed by masonry, except a small opening left for outer fire. In forming the top the fire-openings 32 are arranged at suitable intervals and closed with masonry, the valve 38 in the outlet of such 15 compartment being closed, and the only outlet for the smoke and gases from the fire in the openings 25 at the side of the compartment and from the fire in the opening left in the door being through the row of openings 31. 20 About four of the compartments are fired from the side at the same time, each compartment being separated by the temporary partitions 50 and a new compartment is started every day or so. The partition which 25 separates the compartment that has been thus fired for the longest period is removed and placed at the opposite end of the row of such separated compartments in order to form or separate a new one. The removal of 30 one of the partitions opens the compartment which it separates from the others, so that the heat and gases from the fire introduced into the top of one or more of the compartments can circulate through the same and 35 pass through its passage 36 and valve 38 to the smoke-flue 37 and from thence to the smoke-stack 42.

It will be understood that the valve 38 of such compartment is opened and that the 40 valve in the preceding chamber is closed, and the side fire-openings 25 of such compartment and the opening in the bore 24, also the openings 31, which have been opened to let out smoke and gases, are bricked up or closed 45 when such partition is removed. The fire introduced into the compartment through the tops of the same circulates through the adjacent chambers in the direction indicated by the arrows in Fig. 7, and every day or so 50 the next adjacent compartment is fired from the top through its fire-holes which have been opened by the removal of the masonry or bricks which closed them and now fitted with the metal caps or closures which were 55 before on the fire-holes in the preceding compartment. The fire-holes where the caps were previously situated are now closed with masonry. One or more of the compartments may be fired from the top at the same 60 time.

It will be seen that by first drying out the bricks and raising them to a temperature of about 100° centigrade in separated compartments that are fired from the sides the gases 65 driven from the bricks in other compart-

ments of the kiln will not in any way injure them, because when they are subjected to the same by the removal of the partitions their temperature will be sufficiently high to prevent this. This kiln, which is a combination of the old drying field-kiln and the well-known continuous kiln, is exceedingly economical both in construction and operation. The absence of a permanent arch or top materially lessens the cost of construction, permitting lighter side walls to be used and also permitting them to be spaced at a greater distance apart, and it will also be understood that the kiln-walls can be built considerably higher than in arched kilns, so that the capacity of the kiln is materially increased. The mounting of the temporary tops upon the brick masses in the sections of the kiln permit such tops to drop or lower as the brick masses shrink, thereby preventing the accumulation of hot air in the spaces in the tops of the compartments, as in the kilns having permanent arches. The kiln is economical in operation in that a smaller quantity of fuel is consumed and a greater number 85 of bricks are simultaneously burned in a more perfect manner than in the ordinary continuous kilns.

From the foregoing description, taken in connection with the accompanying drawings, 90 the construction, operation, and advantages of the invention will be readily understood without requiring a more extended explanation.

Various changes in the form, proportion, and the minor details of construction may be resorted to without departing from the principle or sacrificing any of the advantages of the invention as defined by the appended 95 claims.

Having thus described my invention, what I claim as new, and desire to secure by Letters Patent, is—

1. A kiln of the character described, comprising an inner wall, an outer wall surrounding the same and spaced therefrom to form a continuous chamber, said outer wall having filling-openings and fire-openings, removable partitions between said walls for dividing said continuous chamber into separate compartments, temporary tops supported upon brick masses or the like in said chamber and having outlet-openings formed therein, said inner wall having a smoke-passage communicating with the compartments of said chamber, valves for controlling the communication between said passage and said compartments, fire-passages in said temporary tops, and removable closures for said fire-passages, substantially as described. 105

2. A kiln of the character described, comprising a center wall having formed therein a longitudinally-extending smoke-flue located also under this center wall, and inlet-passages adjacent to its bottom communi- 110 115 120 125 130

cating with said flue, valves for controlling said inlet-passages, an outer surrounding side wall spaced from the center wall to form a continuous chamber, said side wall having filling-openings and fire-openings adjacent to its bottom, vertically-removable temporary partitions between said center and side walls to divide said chamber into separate compartments, temporary tops for the compartments of said chamber supported upon the brick masses or the like therein, said tops

having outlet-openings, fire-passages mounted in said tops, and removable caps or closures for said fire-passages, substantially as described and for purpose set forth.

In testimony whereof I have hereunto set my hand in presence of two subscribing witnesses.

PAUL CHMELLEWSKI.
